UNITED STATES PATENT OFFICE.

THEODORE HIRAM PROSKE, OF DENVER, COLORADO.

DRILL-SHARPENER.

1,123,372.

Specification of Letters Patent.

Patented Jan. 5, 1915.

Application filed May 8, 1913. Serial No. 766,287.

To all whom it may concern:

Be it known that I, THEODORE H. PROSKE, a citizen of the United States, residing at 4055 Lowell Boulevard, in the city and county of Denver and State of Colorado, have invented certain new and useful Improvements in Drill-Sharpener; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to improvements in drill sharpeners or apparatus particularly intended for sharpening the drill steels employed for rock drilling purposes.

The special object to be attained in the construction set forth in the drawing and hereinafter described is by the employment of a single manually operated lever to open the valve which admits the motive fluid to the cylinder for operating the piston of the locking device, and also the valve which admits the motive fluid to the horizontal hammer cylinder, the two valve-opening operations being accomplished in the proper sequence. It is important that the locking device or the means for holding the cutting extremity of the drill bit in the stationary position to receive the sharpening blows of the dolly be actuated before the piston with- in the horizontal hammer cylinder begins to operate for reciprocating the dolly. In my improved construction a single lever performs both functions, the construction and arrangement being such that the initial movement of the said lever actuates the valve to admit motive fluid into the locking device cylinder on the side of the piston for actuating the locking mechanism to cause the upper gripping die to engage the drill bit extremity and coöperate with the lower corresponding die to lock the drill bit in position for sharpening purposes; while as the movement of the same lever is continued and in the same direction, the throttle valve for the horizontal hammer is opened and the motive fluid admitted to the cylinder for reciprocating the dolly. It will thus be seen that these two valves are actuated in the proper sequence, without any special attention on the part of the operator, thus making it impossible for a person, no matter

how unskilled he may be in the use of machinery of this kind, to make an error.

It will be understood that if the reciprocation of the dolly were commenced before the drill bit was locked securely in place, the result would be serious.

Having briefly outlined my improved construction, I will proceed to describe same in detail, reference being made to the accompanying drawing, in which is illustrated an embodiment thereof.

In this drawing—Figure 1 is a side elevation of a drill sharpener equipped with my improvements. Fig. 2 is an end elevation of the same, or a view looking in the direction of arrow 2, Fig. 1. In this view the drill bit is shown in cross-section. Fig. 3 is a fragmentary centrally vertical section taken through the structure approximately on the line 3—3, Fig. 2. Fig. 4 is a section taken on the line 4—4, Fig. 3, looking toward the left, the gripping dies, however, being shown in closed position instead of the open position, as in Fig. 3. Fig. 5 is a sectional view taken through the valve mechanism for controlling the passage of motive fluid to the locking device cylinder, the parts being shown on a larger scale than in Figs. 1 and 2. Fig. 6 is a detail view illustrating the valve mechanism for controlling the passage of motive fluid to the horizontal hammer cylinder, the parts being shown in section. Fig. 7 is a similar view, showing the valve and operating parts in the reverse position. Fig. 8 is a fragmentary detail view showing the end lever in a position intermediate the positions shown in Figs. 6 and 7. Fig. 9 is a section taken on the line 9—9, Fig. 8, looking toward the left.

The same reference characters illustrate the same parts in all the views.

Let the numeral 5 designate the main framework of the structure upon which is mounted the vertical hammer cylinder 6, which controls the upper and lower drop dies 7 and 8. However, as this mechanism is quite distinct and separate from the drill-sharpening mechanism proper and the means for controlling the same, to which my present invention more particularly relates, the vertically-disposed hammer mechanism will not be further set forth in detail.

Movably mounted in the framework of the machine are two vertically-disposed parallel rods 9, which are suitably spaced

to receive upper and lower gripping dies 10 and 12, the lower die being stationary and supported by a block 13, while the upper die is movable and connected by means of a bolt 5 or cap-screw 14, with a cross-head 15 mounted on the rods 9. These gripping dies 10 and 12 are fashioned, as shown at 16 and 17, to correspond with the shape of the cutting head of the drill steel when the same is prepared for the sharpening act of the dolly 18, the latter being made fast to the forward extremity of a stem 19, which extends into the horizontal cylinder 20 and is operated by means of a reciprocating piston (not shown) striking the end of said stem for operating the dolly.

A second cross-head 21 is mounted on the two rods 9 and is supported in a pre-determined position by means of nuts 22 threaded upon the rods below the said cross-head.

A link 23 of the locking mechanism is pivotally connected, as shown at 24, with lugs 25, formed on the cross-head 21 and extending upwardly therefrom, the opposite extremity of the link being pivotally connected, as shown at 26, with a horizontally movable cross-head 27, which is connected by means of a piston stem 28 with a piston 29 located within the locking device cylinder 30.

A valve 31 located within the casing 32 regulates the passage of motive fluid to the cylinder 30. The motive fluid is supplied to the valve chamber through an inlet 33 and initially enters a cavity 34 which is alternately in communication with two passages 35 and 36, depending upon the position of the valve.

When this valve is in the position illustrated in Fig. 5, or shifted farther toward the left, the cavity 34 is in communication, through a passage 37 formed in the valve, with the passage 36, which is in communication with a pipe 38, leading to the cylinder 30 forward or to the right of the piston 29 (see Fig. 1). When the valve is in this position, the motive fluid acts on the piston 29 to maintain the link 23 in the position shown in Fig. 3, whereby the upper gripping die 10 is in the raised position and consequently disengaged from the cutting head of the drill steel, assuming that the drill steel is in place as illustrated in the drawing.

Now if it is desired to sharpen the drill steel, the motive fluid must be cut off from the pipe 38 and introduced to a pipe 39, which leads to the cylinder 30 and communicates with the latter in the rear of the piston 29, whereby the said piston is driven forwardly or toward the right (see Fig. 1) and the cross-head 27 actuated to cause the link 23 to approach the vertical position shown in Figs. 1 and 4, whereby the cross-head 21, together with the two rods 9, is moved

downwardly, actuating the upper gripping die 10 to cause the same to assume its lowermost position, whereby it is brought into engagement with the cutting head of the drill steel in co-operation with its companion die 12.

The manner of shifting the valve 31 for the purpose of accomplishing the aforesaid function will now be described. A stem 40 is threaded into the valve 31, as shown at 41, the said stem passing through a stuffing-box 42 in a head 43 of the valve casing or chest. The outer extremity of this stem is pivotally connected, as shown at 44, with a rod 45 which passes through a perforation formed in a lug 46 mounted on the short arm 47 of a bell crank lever 48 which is fulcrumed at 4, the opposite arm 50 of the lever being relatively long and extending forwardly for convenience of hand manipulation. Interposed between the lug 46 and a stop-nut 3 threaded on the forward extremity of the rod 45, is a spiral spring 49 of sufficient stiffness that when the arm 50 of the bell crank lever is pressed downwardly or moved in the direction of the arrow in Fig. 1, the forward movement will be imparted to the rod 45, whereby the valve 31 will be shifted to its forward position, cutting off the motive fluid in the cavity 34 from the pipe 38 and opening communication from the cavity 34 through the passages 51 and 35 to the pipe 39. Within a valve casing 52 is located a valve 60, which is connected by means of a stem 53 with a rod 54, as shown at 55, the forward extremity of the rod 54 being reinforced, as shown at 56. In this reinforcement is formed a slot 57 through which passes a pin 58 carried by the upper extremity of the lever arm 47.

Normally, or when the lever arm 50 begins its downward movement and the arm 47 its forward movement, the pin 58 is in the rear extremity of the slot 57 or the extremity farther to the left, referring to Fig. 1. Hence, during the initial operation of the lever 48 whereby the valve 31 is shifted forwardly and communication established between the cavity 34 of the valve-chest 32 and the horizontal cylinder in the rear of the piston 29, no movement is imparted to the rod 54 or the valve within the casing 52, since the pin 58 carried by the lever arm 47 moves idly in the slot 57, the said slot being of sufficient length to permit the shifting of the valve 31 forwardly for the purpose stated before movement is imparted to the valve within the casing 52. However, as soon as the valve 31 has been properly shifted to its forward position for the purpose aforesaid, the pin 58 has reached the forward extremity of the slot 57, and then as the lever 48 is moved farther in the same direction, the rod 54 is actuated to shift the valve within the casing 52 to its forward

position, whereby the motive fluid is delivered to the horizontal cylinder 20 for reciprocating the piston therein, whereby the dolly is actuated for sharpening the drill steel, as heretofore outlined. After the rod 45 has been actuated to shift the valve 31 to its forward limit of movement, the further movement of the lever 48 in the same direction will serve to compress the spiral spring 49, whereby as soon as the operator releases the lever 48, the recoil of the spring 49 will return the lever to its position at the time of completing the forward movement of the valve 31. Now if it is desired to return the valve 31 to its normal position, whereby the upper gripping die 10 will be raised to disengage it from the drill steel, as is required after the drill-sharpening operation is completed, the movement of the lever 48 will be reversed, and its arm 50 will be moved in the direction opposite the direction of the arrow in Fig. 1, whereby the valve 31 will be shifted rearwardly, the valve within the casing 52 having been already actuated to cut off communication between the horizontal cylinder 20 and the motive fluid, whereby movement of the dolly is stopped. These operations will be completed in the reverse order in which the two valves were originally shifted, that is to say, the valve in the casing 52 will be first actuated to cut off communication with the horizontal cylinder 20 to stop the movement of the dolly, after which the valve 31 will be shifted within the casing 52, whereby the motive fluid will be cut off from the cylinder 30 in the rear of the piston 29 and introduced to the same cylinder forward of the piston 29, whereby the said piston is moved rearwardly and the link 23 actuated to lift the gripping die 10, as heretofore explained.

The manner of operating the valve 60 within the casing 52 is illustrated in Figs. 6 and 7. The manner of opening this valve has heretofore been explained in a general way, namely, by the movement of the arm 47 of the lever 48 after the valve 31 has been shifted to its forward limit of movement, after which the spring 49 is compressed by the engagement of the lug 46 therewith. It should be explained that this lug is pivotally connected with the lever arm 47 to allow it to adjust itself to the varying positions of its lever arm 47. The valve 60 is normally held in the closed position, whereby the motive fluid is cut off from the horizontal hammer cylinder 20 by means of a spring 61 interposed between the valve proper and a stuffing-box 62 of the valve-chest. The operation of the main valve within the chest 52 for controlling the motive fluid for reciprocating the dolly will not be described in detail as nothing is claimed therein, the operation being old in the art.

Assuming now that the drill bit has been sharpened and the operator has released the downward pressure on the arm 50, the recoil of the spring 49, which was compressed during the opening of the valve 60, will first act on the lever arm 47 to actuate the lever 48 and return its arm 47 to its position immediately after the opening of the valve 31 and before the commencement of the operation which opens the valve 60. This position is illustrated in Fig. 8, in which the lug 46 is in engagement with the forward surface of an adjustable stop-nut 63, mounted on the rod 45. The valve 60 being closed, the motive fluid is cut off from the horizontal hammer cylinder 20 and the reciprocation of the dolly stopped. The operator then, by a further movement of the lever 48, in the direction opposite the arrow in Fig. 1, will move the rod 45 rearwardly and return the valve 31 to its rearward position or that shown in Fig. 5, whereby the motive fluid is introduced to the cylinder 30 forward of the piston 29 through the medium of the pipe 38, the said fluid acting on the piston 20 to move the latter rearwardly and return the link 23 to its normal position or that illustrated in Fig. 3, whereby the gripping die 10 is lifted and the drill bit released as will be readily understood.

From the foregoing description, the use and operation of my improved drill sharpener will be readily understood.

Assuming that the machine is at rest and that it is desired to sharpen the drill steel, I shall further assume that the gripping die 10 is in the raised position and that the operating parts of the so-called locking mechanism are correspondingly located. Under these circumstances the lever 48 is in the position illustrated in Fig. 6 of the drawing, while the valve 31 is in a corresponding position. That is to say, the valve 60 which cuts off communication between the motive fluid and the horizontal hammer cylinder 20 is in the closed position. The operator then moves the arm 47 of the lever 48 downwardly or in the direction of the arrow in Fig. 1, whereby the lever is first moved to the position shown in Fig. 8 which moves the valve 31 to its forward position and opens communication between the cylinder 30 in the rear of the piston 29, through the medium of the pipe 38 and other connections as heretofore described. The action of the motive fluid on the piston 29 will move the latter forwardly whereby a corresponding movement is imparted to the cross-head 27 and the link 23 caused to approach the vertical position or that illustrated in Figs. 1 and 4. This movement of the link acts on the cross-head 21 to move the latter together with the rods 9 downwardly, bringing the gripping die 10 into engagement with the head 65 of the drill steel, thus

locking the latter tightly in place for sharpening purposes. The operator will then continue the movement of the arm 7 of the lever 48 in the direction of the arrow in Fig. 1, whereby the lever is moved from the position shown in Fig. 8 to that shown in Fig. 7. It will be understood that during the movement of the lever from the position in Fig. 6, to that in Fig. 8, the spring 49 has not been compressed, since its tension or strength is such that the forward movement of the valve 31 requires less resistance than would be necessary to compress this spring. Consequently the spring is in its normal or expanded position until the lever begins to move from the position in Fig. 8 toward the position in Fig. 7. The collar 46 then begins to move forwardly on the rod 45 and away from the stop-nut 63, since the rod 45 cannot move farther forwardly as its valve 31 is at its forward limit of movement in the valve-chest 32, being in engagement with the head 43 of the said chest. Hence, during the movement of the lever 48 from the position shown in Fig. 8 to that shown in Fig. 7, the spring 49 is compressed and the collar 46 moves forwardly from the stop-nut 63, far enough to open the valve 60 and admit motive fluid to the horizontal hammer cylinder.

It should be further explained that during the movement of the lever 48 from the position shown in Fig. 6 to that shown in Fig. 8, the pin 58, which connects the lever arm 47 with the rod 54, moves in the slot 57 and consequently there is no movement of the rod 54 or of the valve 60 until after the valve 31 is shifted to its forward limit of movement and the motive fluid delivered to the cylinder 30 in the rear of its piston. However, during the movement of the lever from the position in Fig. 8 to that in Fig. 7, whereby the spring 49 is compressed, the rod 54 moves forwardly, whereby the valve 60 is opened and the motive fluid allowed to pass to the horizontal hammer cylinder 20 for the purpose of reciprocating the piston striking the dolly stem for drill steel sharpening purposes. The operator will then hold the lever 48 in the position shown in Fig. 7 until the sharpening operation is complete. He will then release the pressure on the arm 47 of the lever and the recoil or expansion of the spring 49 will first return the lever automatically to the position shown in Fig. 8, and the spring 61 in the meantime will automatically act on the valve 60 to close the latter and cut off the motive fluid from the horizontal hammer cylinder 20 and stop the movement of the dolly. The operator will then move the arm 50 of the lever 48 in the direction opposite the arrow in Fig. 1, whereby the lever arm 47 will act through the medium of its collar 46 and the stop-nut 63 on the rod

45 to move the latter rearwardly and return the valve 31 to its rearward position, whereby the motive fluid is cut off from the cylinder 30 in the rear of the piston 29, and introduced into the same cylinder forward of 70 the said piston, through the medium of the pipe 38. In this event, the piston 29 will be moved rearwardly and the link 23 returned to the position shown in Fig. 3, whereby the gripping die 10 is raised and 75 the drill bit released, thus permitting it to be removed from the machine which is then ready to receive another drill bit, when the operation may be repeated.

I claim—

1. In mechanism of the class described, the combination of two valve chests and two valves, rods connected in operative relation with the valves, a lever suitably fulcrumed, a perforated lug mounted on one arm of the 85 lever and through which the first rod passes, a stop-nut mounted on the said rod in the rear of the lug, a second stop-nut mounted on the rod forward of the lug, a spiral spring interposed between the lug and the 90 forward stop-nut, the spring being of sufficient tension to resist compression during the valve-operating movement of the first rod, the second rod having a slot through which a pin carried by the said lever arm 95 passes, the arrangement being such that the movement of the lever to actuate the first rod for valve-operating purposes causes the pin carried by the said lever arm to travel idly in the slot of the second rod until its 100 forward extremity is reached, after which the movement of the lever in the same direction actuates the second rod to operate its respective valve, substantially as described.

2. In a drill sharpening machine the combination of two valves, a lever, an operative connection between the lever and both valves to open the latter in succession during the movement of the lever in a given direction, the connection and arrangement of 110 parts being also such that the valve first opened remains inactive during the opening movement of the second valve, means for automatically returning the lever to the position it occupied when the opening movement of the first valve was completed, means for automatically and simultaneously closing the second valve while the first valve is still open and fluid operated means controlled by said valves for locking a drill in 115 position to be sharpened and for performing the sharpening operation.

3. In a drill sharpener, the combination with a reciprocable device arranged to act on the drill steel to perform the sharpening function, and a locking device for holding the drill steel in place during the sharpening operation, said locking device including a pair of movably mounted, parallel vertically disposed rods, a jaw mounted 125

80

105

110

115

120

125

130

1,123,872

upon the upper extremities of said rods and adapted to coöperate with a stationary jaw located below said first named jaw and between the said rods, means for operating 5 the locking device, and a link connecting the said operating means and the vertically disposed rods, substantially as described.

In testimony whereof I affix my signature in presence of two witnesses.

THEODORE HIRAM PROSKE.
